DESIGN FOR A BORDER FOR LACE EDGING.

Specification for Design.

Patented June 2, 1914.

Application filed February 25, 1914. Serial No. 821,011. Term of patent 7 years.

To all whom it may concern:

Be it known that I, CHARLES W. H. KOSTENBADER, a citizen of the United States, residing in Philadelphia, county of Philadelphia, and State of Pennsylvania, have invented a new, original and ornamental Design for a Border for Lace Edging, of which the following is a specification, reference being had to the accompanying drawings, which form a part thereof.

In lace edgings, particularly that variety thereof applied to ladies' underwear, the same usually consists: first, of the body of the edging forming the braiding space, of which there are a limited number of commonly employed designs; and second, of an ornamental knitted tip or border, attached to the body along one longitudinal edge thereof, said ornamental tip or border em-

bodying, in different edgings, a variety of designs. A fabric exhibiting my new design is intended for use as such ornamental tip or border, although the same is adapted to be used independently of an edging body.

Figure 1 is a plan view of a number of repeats of such an ornamental tip or border embodying my new design. Fig. 2 is a similar view enlarged.

I claim—

The ornamental design for a border for lace edging, as shown and described.

In testimony of which invention, I have hereunto set my hand, at Philadelphia, on this 24th day of February, 1914.

CHARLES W. H. KOSTENBADER.
